UNITED STATES PATENT OFFICE.

JOSEPH G. LAMOTTE AND JOHN B. LAMOTTE, OF WORCESTER,
MASSACHUSETTS.

SIFTING ATTACHMENT FOR GRATES.

SPECIFICATION forming part of Letters Patent No. 769,950, dated September 13, 1904.

Application filed February 27, 1904. Serial No. 195,512. (No model.)

To all whom it may concern:

Be it known that we, JOSEPH G. LAMOTTE and JOHN B. LAMOTTE, citizens of the United States, residing at Worcester, in the county 5 of Worcester and State of Massachusetts, have invented a new and useful Sifting Attachment for Grates, of which the following is a specification.

This invention relates to an attachment for 10 use in connection with the grates of stoves or other fire-pots.

The especial object of this invention is to 15 combine a rotary shaking or dumping mechanism of a grate with a reciprocating screen for sifting the ashes.

To these ends this invention consists of the 20 sifting attachment for grates and of the combinations of parts therewith, as hereinafter described, and more particularly pointed out in the claims at the end of this specification.

In the accompanying drawings, Figure 1 is 25 a sectional view of sufficient parts of a stove to illustrate the application of our invention thereto, and Fig. 2 is an enlarged detail view showing the operative connections between the rotary shaking or dumping mechanism of a grate and a vibrating screen.

In connection with the grate of a stove or 30 other fire-pot of that type employing a rotary handle for shaking or dumping we have provided an inclined sifting-screen which will be vibrated back and forth to shift the ashes whenever the grate is operated.

Referring to the accompanying drawings 35 and in detail, the body portion of the stove, as herein illustrated, incloses an oven A and a fire-pot P, which may be lined with fire-brick in the ordinary way.

The grate herein illustrated comprises the 40 side pieces 10, having inwardly-projecting fingers or grate-bars which coöperate with the triangular grate-bar sections mounted upon the shafts 11 and 12. The grate-bar shafts 11 and 12 are geared together at one end by 45 means of spur-gears 13 and 14. In the space below the grate is an inclined screen 15. As shown most clearly in Fig. 2, the screen 15 is provided at its ends with projecting rods 16, which may be mounted in suitable blocks or

bearings to permit the screen to be vibrated 50 or moved back and forth.

Fastened upon the operative shaft 11 of the grate-bars is a beveled gear 17, which meshes with a beveled pinion 18 on the upper end of a vertical shaft 19. The vertical shaft 19 is 55 provided with a bent or cranked section connected by a link 20 to operate the vibratory screen 15. By means of this construction whenever the grate-bars are oscillated to shake the fire or rotated to dump the fire—for example, by means of a handle 23—the screen 15 will be vibrated or moved back and forth to sift the ashes.

Below the inclined screen 15 we provide an 60 ash tray or box 21, and in front of the ash tray or box 21 we provide a coal tray or box 22.

In the use of a stove having an attachment for its grate as thus constructed the ashes or other material which passes through the grate when the fire is shaken or dumped will fall 70 upon the inclined screen 15, and the ashes which pass through the screen will fall into the ash tray or box 21, while the coal and coarser materials will be directed down the inclined surface of the screen and will fall 75 into the coal tray or box 22. By means of this construction the ashes will be efficiently sifted and separated from the coal or other coarser materials.

We are aware that numerous changes may 80 be made in applying our invention to different types of stoves by those who are skilled in the art and that different forms of grate-bars may be used in connection with our sifting attachment. We do not wish, therefore, to be limited to the special construction we have herein 85 shown and described; but

What we do claim, and desire to secure by Letters Patent of the United States, is—

1. The combination of a fire-grate comprising a plurality of grate-bars, each consisting of a pivoted shaft having extending arms, and a sifting-screen having a rectilinearly-recipro- 90 cating motion imparted thereto from the turning of the grate-bar shafts.

2. The combination of a fire-grate consisting of a plurality of pivoted shafts geared to turn together, each of said shafts having ex- 95

- tending arms, means for turning the shafts, an inclined sifting-screen below the grate, connections for imparting rectilinearly-reciprocating motion to the inclined sifting-screen from the turning of the grate-bar shafts, a receptacle for receiving the sifted material which passes through the grate-bars, and a receptacle at the front of the inclined sifting-screen for receiving the unsifted material.
- 10 3. The combination of a fire-grate, having grate-bars, an operating-shaft for the grate, an inclined sifting-screen below the grate and movable longitudinally with respect thereto,

an ash-receptacle below the sifting-screen, a receptacle for receiving the coal deflected by 15 the inclined screen, a crank-shaft connected to move the screen and beveled gears connecting the crank-shaft and grate-operating shaft.

In testimony whereof we have hereunto set our hands in the presence of two subscribing 20 witnesses.

JOSEPH G. LAMOTTE.
JOHN B. LAMOTTE.
